UNITED STATES PATENT OFFICE.

LEWIS A. HAINES, OF HARRISBURG, PENNSYLVANIA.

BALANCED VALVE.

SPECIFICATION forming part of Letters Patent No. 365,680, dated June 28, 1887.

Application filed April 2, 1887. Serial No. 233,438. (No model.)

To all whom it may concern:

Be it known that I, LEWIS A. HAINES, a citizen of the United States, residing at Harrisburg, in the county of Dauphin and State of Pennsylvania, have invented certain new and useful Improvements in Balanced Valves; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

15 Figure 1 of the drawings is a vertical longitudinal section of a cylinder and steam-chest, showing my improved balanced valve. Fig. 2 is a sectional view of pressure-plate and shoe. Fig. 3 is a detail view of shoe. Fig. 4 is a front view and an end view of pressure-plate. Fig. 5 is a horizontal transverse section of cylinder and steam-chest; Fig. 6, a detail view of steam-chest; Fig. 7, a detail and sectional view of valve; Fig. 8, a detail and 25 sectional view of pressure-plate.

The invention relates to improvements in balanced valves, the object being to take up the wear of the valve and keep the joint between the valve and its seat tight; and it consists in the construction and arrangement of a spring-controlled shoe fitted to and movable upon the pressure-plate above the valve, and in the combination of the same with certain other parts, as hereinafter set forth.

35 Referring to the drawings, A designates the cylinder, B the piston with its rod attached, C the steam-chest, c c the steam-ports, and c' the exhaust.

D is the valve, with its stem passing through 40 a stuffing-box in the usual manner. The valve is rectangular in form, having the central exhaust-opening, d, and the steam-passages in openings d' d' near its ends.

d' is a central longitudinal sleeve or tube 45 forming part of the valve and having the end part of the valve-stem secured within it, as shown.

E is the pressure-plate, rectangular in form and sufficiently wide to have its side edges rest 50 upon the edges of the walls e e, rising on each side of the valve-seat e', and between which

walls the valve is fitted, as shown. The said pressure-plate E has a central exhaust-chamber, e², and the similar steam-channels e³ e³ in its front and rear edges, registering with or opposite to the orifices of the steam-ports c c, and having the same width as said openings. 55

F is a coiled spring resting in a central circular recess in the outer surface of the pressure-plate, an inwardly-standing boss being 60 formed integrally with said plate, in which to make said recess. The said spring keeps the pressure-plate pressed on the edges of the walls e, which are flush with the upper surface of the valve. The pressure-plate is held in place 65 laterally by abutting against the shoulders f f on the interior of the steam-chest, and from front to rear by abutting against the shoulders f' f' within the same.

G is a shoe rectangular in shape and provided at its rear and front ends with the outwardly-standing flanges g g, between which the inwardly-standing flanges g' g' on the front and rear ends of the pressure-plate are fitted. 70

g² g² are steam spaces or openings in the front 75 and rear parts of the shoe, which spaces are continuous with the steam-channels e³ e³ of the pressure-plate. The side edges, h h, of the shoe are fitted between the inwardly-standing side flanges, H H, of the pressure-plate, which 80 flanges rest upon the walls e e on each side of the valve-seat e'. The pressure-plate has at its corners the recesses I, in which the coiled springs J bear down on the plates j j, which lie upon the shoe between the flanges g g, so 85 that the shoe can be forced inward in relation to the pressure-plate. The tops of the flanges g g are preferably rounded, as shown in the drawings, and the joint K between the upper side of the shoe and lower side of the pressure-plate is sufficiently open to receive steam. 90

When the parts are fitted together and in operation, the steam-pressure on the inner and outer ends of the flanges g will be equal and balance, and the steam-pressure in the joint K 95 will at all times balance the pressure upon the parts of the edges of the flanges g' of the pressure-plate that are outward from the steam-openings g², for when the parts e and openings g² are open to receive live steam the latter will 100 fill the joint K, and when the ports and openings are closed the compressed steam flowing

from the cylinder will fill said joint. When either port begins to take steam, the latter flows both directly into the port to the inner side of the valve, and also to the outer side of the 5 valve into the opening *g*, so that the same amount of valve movement gives double the valve-opening than in the ordinary slide-valve.

The shoe cannot be moved from its seat by the compressed steam passing out of the steam- 10 ports, as the said steam passes through the openings in the shoe, and its pressure acts upon the pressure-plate, which is backed by steam in the steam-chest.

Having described this invention, what I 15 claim, and desire to secure by Letters Patent, is—

1. The combination, with the balanced slide-valve, of a pressure-plate and a shoe guided by the pressure-plate and automatically moved 20 inward thereon by springs, so as to bear on the valve, take up the wear of the same, and maintain the joints between the valve and its outer and inner seats steam-tight, substantially as specified.

25 2. The combination, with the balanced slide-valve, of a pressure-plate and a shoe guided by the pressure-plate and movable toward the valve thereon, whereby the wear of the valve is taken up and the joints between the valve 30 and its inner and upper seats are maintained steam-tight, substantially as specified.

3. The combination, with the balanced slide-valve having steam and exhaust openings through it, of a pressure-plate and a shoe 35 guided by and movable toward the valve on the pressure-plate and provided with steam-

channels registering with the orifices of the steam-ports, so that the ports will take steam directly, and also through the channels in the shoe, substantially as specified. 40

4. The combination, with the two-faced balanced valve, of the shoe on the outer face of said valve, and means, substantially as described, whereby the shoe is equally balanced at all points of the valve travel, substantially 45 as specified.

5. The combination, with the two-faced balanced valve having the exhaust and steam openings through it, of the shoe provided with steam-openings to properly register with the 50 steam-ports of the cylinder, and the pressure-plate outside of the shoe and kept to its seat thereon by springs, substantially as specified.

6. The combination, with a balanced valve having steam and exhaust openings through 55 it, of the pressure-plate kept to its seat by a spring or springs, and the shoe provided with the flanges *g g*, which fit each end of the pressure-plate, forming a joint therewith, into which steam enters to balance the shoe, substantially 60 as specified.

7. The combination, with a balanced valve, of the pressure-plate, the shoe guided by said plate, and the springs *J* in the recesses *I* of the pressure-plate, bearing on the plates *j*, which 65 rest upon the shoe, substantially as specified.

In testimony whereof I affix my signature in presence of two witnesses.

LEWIS A. HAINES.
